UNITED STATES PATENT OFFICE

118,856

DESIGN FOR A COMBINED WORKBENCH AND CABINET OR SIMILAR ARTICLE

George M. Graham, Detroit, Mich., assignor to Hinckley-Myers Company, Jackson, Mich.

Application October 9, 1939, Serial No. 87,583

Term of patent 3½ years

To all whom it may concern:

Be it known that I, George M. Graham, a citizen of the United States, residing at Detroit, in the county of Wayne and State of Michigan, have invented a new, original, and ornamental Design for a Combined Workbench and Cabinet or Similar Article, of which the following is a specification, reference being had to the accompanying drawing, forming part thereof.

In the drawing:

Figure 1 is a perspective view of a combined workbench and cabinet or similar article showing my new design, and

I claim:

The ornamental design for a combined workbench and cabinet or similar article, as shown.

GEORGE M. GRAHAM.
